UNITED STATES PATENT OFFICE.

JOHN WILLIAM PIPPIN, OF BROWNWOOD, TEXAS.

OIL-BURNER.

No. 915,475.

Specification of Letters Patent. Patented March 16, 1909.

Application filed December 17, 1907. Serial No. 406,856.

To all whom it may concern:

Be it known that I, JOHN WILLIAM PIPPIN, a citizen of the United States, residing at Brownwood, in the county of Brown and 5 State of Texas, have invented a new and useful Improvement in Oil-Burners, of which the following is a specification.

My invention is an improvement in oil burners and consists in certain novel constructions and combinations of parts herein- 10 after described and claimed.

Referring to the drawings forming a part hereof, Figure 1 is a perspective view of a range provided with my improved burner. 15 Fig. 2 is a plan view of the burner. Fig. 3 is a section on the line 3—3 of Fig. 2. Fig. 4 is a section on the line 4—4 of Fig. 2. Fig. 5 is a longitudinal section through the oil heater. Fig. 6 is a vertical section through the cover 20 of the water box and the parts attached.

In the present embodiment of my invention, the burner is shown applied to a range E, and comprises the burner A to be presently described, a water tank or container B, 25 connected to the burner by a flexible tube b, and a fuel supply tank C, supported by a stand c, and connected to the burner by a tube c'.

The burner A comprises an oil heater a⁰, a 30 boiler a, a water box a', a steam dome a² and an atomizer a³. The box a' is provided with covers a⁴, secured to the box by screws a⁵, and one cover has arranged therethrough a nipple a⁶, provided with a valve seat, in which 35 works a needle valve a⁷, pivoted to one arm of an elbow lever a⁸, having its trunnions journaled in a bracket a⁹ on the inner face of the cover, and having a float a¹⁰ connected with the other arm.

40 The flexible tube b leading from the water tank B is connected with the nipple, and the flow of water from the tank to the box is controlled by the float a¹⁰, the water in the box, and as a consequence the water in the boiler, 45 being retained at a predetermined level.

The water box a' communicates with the boiler a by a relatively small water port a¹¹, near the bottom of the boiler, and by a relatively large steam port a¹², near the top of 50 the boiler, as shown in Fig. 3, and the boiler communicates with the steam dome a², by a

port a¹³ leading from the top of the boiler. Within the dome is a pipe a¹⁴ opening near the top of the dome, and extending through the bottom thereof, the outer end being 55 threaded for connection with the atomizer a³.

The atomizer comprises a pipe a¹⁵ extending toward the fire box e of the range, and having at its inner end a small opening a¹⁶. A T, a¹⁷ is threaded on the outer end of the 60 pipe a¹⁵, and the lateral branch of the T is threaded on the lower end of the steam dome pipe a¹⁴. A short pipe a¹⁸ is threaded in the outer end of the T, and a second T, a¹⁹ is threaded on the pipe a¹⁸. A discharge valve 65 a²⁰ is connected with the outer end of the T, and a pipe a²² provided with a valve a²³ connects the lateral branch of the T with the top of the oil heater a⁰, to be presently described. The pipe a¹⁸ is of relatively small internal di- 70 ameter, and a small tube a²¹ is fastened into the opening, the tube extending to a point adjacent to the opening of the atomizer. The free end of the said tube is supported by a spider a²³, and is provided with a nozzle a²². 75 The atomizer discharges onto a spreader a²⁴ which is adjustably supported in a pan a²⁵, arranged in the fire box, and provided at its ends with brackets a²¹, upon which the boiler is supported. An oil leader a²⁶ is adjustably 80 connected with the end of the atomizer pipe by a set screw a²⁷, and assists in directing the spray of oil against the spreader. The spreader is slideable in the pan and may be moved from one end to the other being supported on ledges a²⁸ as shown in Fig. 2. 85

The oil heater a⁰, comprises a cylindrical casing, connected on its bottom side with a tube c' communicating with the tube c, which communicates with the oil tank C, the 90 pipe a²⁹ before mentioned leading from the top side of the casing. By means of the valve a³³, the supply of oil to the atomizer may be regulated, and as a consequence the intensity of the fire. 95

A pop-off valve a²⁸, is arranged adjacent to the steam dome and communicates with the bottom thereof, as at a²⁹, and a pipe a³⁰ leads from the pop-off valve to and through the oil heater a⁰ and into a drain pipe a³². 100 The drain pipe a³² leads from the pan a²⁵, opening above the bottom thereof, and is

adapted to carry away any excess of oil in the pan. The pop-off valve may be adjusted to any predetermined pressure, and carries off the excess and wet steam passing it through the heater and warming the oil therein so that it becomes thin and light, and in excellent condition for atomizing.

A valve a^{34} is arranged between the water tank and the water box, and a drain valve a^{35} 10 is connected with the water box. By means of these valves, the water may be cut off from the boiler and box, and they may be drained to prevent freezing. The valve at the outer end of the atomizer pipe permits 15 cleaning of the atomizer tube, should for any reason said tube become choked. The removable cover or head of the water box is provided with a glass covered peep-hole a^2 , and the arm of the elbow lever is threaded so 20 that the float may be adjusted, to maintain the water at different levels.

The oil tank may be arranged at any suitable point, usually outside of the house, but the water tank should be inside. Said tank 25 is shown supported by a cord b' connected with the tank and passing over a pulley b^2 , secured to the ceiling, so that the tank may be raised or lowered to insure a water pressure in the water box greater than the steam 30 pressure.

In operation, the tanks being supplied with oil and water respectively, oil is admitted to the pan and ignited. The heat will soon generate steam which will pass into the 35 steam dome, from whence the dry steam passes to the atomizer, spraying the oil from the heater onto the spreader. The excess steam passes through the heater, heating the oil therein, in its passage, and discharges 40 through the discharge pipe.

It will be evident from the description that the oil, steam and water are each automatically controlled, so that enough of each is supplied to insure a perfect combustion 45 with no soot, odor or smoke. Either light or heavy grades of oil may be made use of.

It will be evident from the description that the steam is delivered to the atomizer at a steady and predetermined pressure, and that 50 the excess steam above the pressure is utilized to heat the oil previous to its entrance into the atomizer.

I claim—

1. An oil burner comprising a water box, 55 means for supplying water to the box, a float valve in the box for controlling the supply, a boiler having a lower relatively small water port and an upper relatively large steam port communicating with the water box, a steam 60 dome, communicating with the top of the boiler, a vertical pipe in the steam dome, said pipe opening near the top of the dome,

and extending through the bottom thereof, a pan below the boiler, a spreader in the pan, an atomizer connected with the steam dome 65 pipe and discharging onto the spreader, an oil heater communicating with the atomizer, means for supplying oil thereto, a waste pipe leading from the pan, a pop-off valve in connection with the steam dome, and a pipe 70 leading from the pop-off valve through the oil heater and into the waste pipe.

2. An oil burner, comprising a boiler, means for supplying water to the boiler, means for retaining the water in the boiler at 75 a predetermined level, a steam dome, with which the upper part of the boiler communicates, a vertical pipe in the steam dome, said pipe opening near the top and extending through the bottom of the dome, a pan below 80 the boiler, a spreader in the pan, an atomizer connected with the steam dome pipe and discharging onto the spreader, an oil heater communicating with the atomizer, means for supplying oil thereto, a waste pipe leading 85 from the pan, a pop-off valve in connection with the steam dome, and a pipe leading from the pop-off valve through the oil heater and into the waste pipe.

3. An oil burner, comprising a boiler, 90 means for supplying water thereto, means for retaining the water in the boiler at a predetermined level, a pan below the boiler, a spreader in the pan, a steam dome in connection with the boiler, an atomizer connected 95 with the dome and discharging onto the spreader, an oil heater delivering to the atomizer, means for regulating the flow of oil from the heater, a safety valve on the dome, and means in connection with the valve for 100 receiving the excess steam and passing it through the heater.

4. An oil burner comprising a boiler, means for supplying water thereto, a spreader below the boiler, a steam dome in connection with the boiler, an atomizer connected to the dome and discharging onto the spreader, an oil heater delivering to the atomizer, a safety valve in connection with the dome, and means in connection with the 105 valve for receiving the excess steam and passing it through the heater.

5. An oil burner comprising a boiler, a spreader below the boiler, an atomizer, means for conducting steam from the boiler 115 to the atomizer, a spreader below the boiler onto which the atomizer discharges, an oil heater delivering to the atomizer, a safety valve in connection with the boiler, and means for receiving the excess steam from 120 the valve and passing it through the heater.

6. An oil burner comprising a boiler, an atomizer, discharging below the boiler, means for conducting steam from the boiler to the

atomizer, an oil heater delivering to the atomizer, a safety valve in connection with the boiler, and means for receiving the excess steam from the valve and passing it through the heater.

7. An oil burner comprising a boiler, an atomizer connected with the boiler, means for supplying steam at a predetermined pressure to the atomizer, a pop-off valve in

connection with the boiler, and means for 10 heating the oil previous to its entrance into the atomizer with the excess steam passing from the pop-off valve.
